UNITED STATES PATENT OFFICE.

GEORGES CLAUDE, OF PARIS, FRANCE, ASSIGNOR, BY MESNE ASSIGNMENTS, TO
LAZOTE INC., A CORPORATION OF DELAWARE.

APPARATUS FOR THE SYNTHESIS OF AMMONIA.

Application filed December 22, 1921, Serial No. 524,087. Renewed December 17, 1926.

This invention relates to apparatus for use in the synthetic production of ammonia.

In the synthesis of ammonia, particularly with processes involving the use of hyper-
5 pressures, the enormous working activity of the catalyzing material brings about a relatively rapid deterioration of this material, especially if, owing to fortuitous circumstances, the purity of the gas leaves anything
10 to be desired or if, in consequence of faulty regulation or faulty internal arrangements, the internal temperature becomes too high.

It is, therefore, of the highest importance to be able with great facility to renew the
15 catalyzing material after deterioration of the same. In this connection the extremely reduced dimensions of the reaction tubes for a given output consequent upon the extreme
20 reduction of the volume of the gases and the enormous activity of the formation of ammonia, already assist in obtaining this result, but in a manner which is still inadequate.

The present invention contemplates the
25 provision of means which overcome the difficulties hitherto experienced in the replacement of the catalyzing material and which enable this replacement to be carried out quickly and with ease. The particular de-
30 vices adapted for obtaining the desired re-
sults in accordance with this invention are especially applicable to the process which has been described in the co-pending patent ap-
plication of Georges Claude, Serial No.
35 516,045 filed November 18, 1921.

The process described in the above men-
tioned application takes into account the ne-
cessity of practically suppressing the elimi-
nation of the heat of reaction through the
40 walls of the pressure supporting tube, with a view to avoiding explosions through exces-
sive expansion of their internal layers. The characteristic feature of this process consists in fact in carrying away a quantity of heat
45 equal to the heat of the reaction in the is-
suing gases and in abandoning the practice which consisted in bringing the entering gases up to the temperature of reaction at the expense of the heat of the gases which have
50 left the catalyzing material. The process according to the patent applications men-
tioned above consists, therefore, in introduc-
ing the gases into the enclosure where the reaction takes place without having heated
55 them, or but little, and in causing them to

circulate along an inner tube containing the catalyzing material and affording at each point a thermal conductivity such that at the point in question the quantity of heat re-
60 moved from the gases in the inner tube is as exactly as possible equal to that which is pro-
duced at this same point by the reaction.

According to the present invention in an apparatus for the synthetic production of am-
65 monia the member constituting the closure of the outer pressure supporting tube car-
ries a conduit which constitutes the exit tube for the gases after reaction, the said conduit being continued beyond said member so as to project into the interior of the pressure
70 supporting tube and carrying on its extend-
ed portion the inner tube containing the cat-
alyzing material. With this construction of
apparatus the closure member and the inner
75 tube may be easily and quickly removed for
effecting the renewal of the catalyzing ma-
terial.

In order that the invention may be clearly understood and readily carried into effect the same will now be more fully described
80 with reference to the accompanying draw-
ings in which:

Figure 1 shows in section one form of the improved apparatus according to the pres-
85 ent invention.

Figures 2 and 3 show details of the ar-
rangement in which the closure-member or
head is provided with an interrupted screw-
thread.

In Figure 1 the pressure-supporting tube
90 H is made of a special metal adapted to re-
sist the action of the gases present, for ex-
ample of steel containing a high percentage
95 of nickel, such as one of the steels com-
mercially known as A T G or B T G; this tube
is insulated externally against the conduction
of heat as far as the vicinity of its head D;
which is screwed to the inside of the tube
100 H with an hermetic joint F of the smallest
diameter possible so as to call into play the
minimum amount of effort both for closing
and for resistance to pressure.

The catalyzing material C is placed in
an inner tube T having an external heat in-
sulating coating E of decreasing thickness,
105 and the reacting gases which enter through
the orifice A, which may be located upon the
head D or laterally upon the tube H, circu-
late in the annular space B around the heat
insulated tube T—E. The tube T is con-
110

nected to the head by means of the tube L which serves for the escape of the gases and, if necessary, the parts may also be connected by means of the lag-bolts G, while at the 5 other end the tube is provided with a detachable plug R furnished with gauze covers U. Under these conditions, the inner tube T—E may easily be removed by unscrewing the head D to which it is attached and, in order 10 thereupon to replace the catalyzing material, it suffices to remove the plug R.

It will be seen that this replacing operation is effected easily and without having to interfere with the external tube H, which is by far 15 the heaviest part of the apparatus and which may remain permanently in position, together with its electric heating circuits S, in its insulated receptacle, and can thus be maintained without difficulty at the reaction tem- 20 perature.

To facilitate the dis-assembly, the end of the tube H is provided, for example, with two small flat parts J which fit into a recess made in a very thick fixed metal plate K. This 25 metal plate thus plays the part of a counter-spanner when acting with a spanner upon the head D.

The invention includes, furthermore, the facilitation of the renewal of the catalyzing 30 material to the point of rendering such renewals almost as simple as the replacing of a projectile in a gun of large calibre.

In this connection it will be remarked that one of the consequences of the method of circulation of the gases hereinbefore referred to 35 is that the temperature of the pressure-supporting tube H decreases progressively along its length, from the end where the hot gases penetrate into the catalyzing material and 40 where this temperature is equal to the reaction temperature up to the other end which carries the head D where this temperature but slightly exceeds the surrounding temperature. Were the head also at a temperature 45 only slightly raised then the conditions as regards tightness of the joint F, and of non-gripping of the screw threads in case of frequent dismountings, could be satisfactorily complied with by maintaining good lubrica- 50 tion of the screw threads. In order to obtain this result it suffices to arrange as far as possible for the intimate contact with the head of the cold or slightly heated entering gases and to prevent as far as possible contact with the 55 issuing hot gases. With this object the gases may be made to pass out through a central tube L separated from the head by an asbestos lining M and hermetically sealed by means of a stuffing box M' packed with asbestos or by 60 means of a countersunk joint.

The cold gases on the contrary enter in direct contact with the metal, through the orifice A and the annular conduit O which distributes them symmetrically in such manner 65 as to prevent any inequalities of temperature

which would deleteriously affect the tightness of the joint. The tube L through which the gases issue must be made of metal which is capable of supporting their high temperature. The connection with the tube or steel 70 coil for conducting these gases to the ammonia liquefier is effected by means of a connection N immersed in water. The head D may be made of a metal which fits as well as possible from the point of view of gripping of the 75 screw threads, the metal of special type of which the pressure-supporting tube is formed; it may, for example, be made of mild or semi-hard steel in the case where the special steels mentioned above are used for the 80 tube H.

In order to quickly replace the catalyzing material, it would hardly be practical, after having unscrewed the connected parts T D, to remove the used up material, refill the tube T 85 with fresh "non-formed" material (i.e. not reduced by hydrogen), again screw up the connected parts T D in the tube H and then "form" the catalyzing material. The present invention provides that, after exhaustion of 90 the catalyzing material, the connected parts T D are replaced by another identical part already "formed" in another supplementary 95 external tube by means of hydrogen or preferably by the small hyper-compressed gaseous residue still containing hydrogen issuing from the last catalyzer tube of the plant during normal working.

In this latter case the ammoniacal gases produced may be sent on issuing from this 100 supplementary tube into a sulphuric acid absorber and the final residue can be returned to the hydrogen-making plant. As the output of gas in this supplementary tube is very 105 low, and as the effect of the internal heat insulating lining E is less than that under conditions of normal output, it may happen that when the reduction is very advanced the tube rises in temperature despite all the heating circuits being cut off. It will suffice to reduce 110 the pressure of the gaseous residue feeding this tube by means of a regulating cock in order to successfully control this tendency.

Under the conditions thus depicted even the unscrewing of the head D becomes a 115 lengthy operation in consequence of the compulsory length of the screwed portion, especially if the operation has to be simultaneously effected for the different tubes of one installation. Consequently this continuous 120 thread indicated in Fig. 1 may be replaced by an interrupted thread shown in Figs. 2 and 3, the threaded portions engaged together being a, b and c similar to that used in the breech of a gun. The construction is such 125 that, on forcing in the tube T so that the head D goes home, a rotation of one fourth or one sixth of a revolution is sufficient to effect engagement of the male and female threads, the rotation being effected for example by 130

the aid of a handle controlling through a tangent screw a toothed crown made in the head D; in this way there can be crushed a very thin packing ring at F and tightness can 5 easily be ensured. The single tangent screw may be replaced by two screws placed symmetrically as shown in Figures 2 and 3 and mounted in bearings X¹, X², X³ and X⁴ on the plate K. These two screws V are controlled, for example, by a handle P through 10 gearing P' which permits of a considerable reduction of the effort necessary for crushing the packing ring at F and for obtaining the tightness. More simply, by means of a 15 handle a toothed wheel mounted upon the axis of one of the two screws and engaging with a second similar toothed wheel mounted upon the axis of the other screw may be caused to rotate direct. These same figures show 20 that the head D and the tube H are provided respectively with male and female interrupted screw threads.

When the head is in place it suffices to screw the gas inlet and outlet tubes thereto by means 25 of the connections A and N, the latter being then immersed in cold water as has been explained.

Various changes may be made in the details 30 of arrangements of the parts as hereinbefore described without departing from the invention or sacrificing any of the advantages thereof.

I claim :

1. An apparatus for the synthetic production 35 of ammonia in which a member constituting a closure of the outer pressure supporting tube carries a conduit for the gases, the said conduit being continued beyond said member so as to project straight-forward into 40 the interior of the pressure-supporting tube and carrying on its extended portion an inner tube containing the catalyzing material.

2. An apparatus for the synthetic production 45 of ammonia in which a member constituting a closure of the outer pressure-supporting tube carries a conduit for the gases, the said conduit being continued beyond said member so as to project straight-forward into 50 the interior of the pressure-supporting tube and carrying on its extended portion an inner tube containing the catalyzing material, and means whereby the gases that are to undergo 55 reaction are admitted into the space between the outer pressure-supporting tube and the inner tube at that end of the apparatus where the closure member is located.

3. An apparatus for the synthetic production 60 of ammonia in which a member constituting a closure of the outer pressure-supporting tube carries a conduit thermally insulated therefrom, which conduit constitutes the exit tube for the gases after reaction, said conduit being continued beyond said member so as to project straight-forward into the interior 65 of the pressure-supporting tube and

carrying on its extended portion an inner tube containing the catalyzing material, and means whereby the gases that are to undergo reaction are admitted into the space between the outer pressure-supporting tube and the inner tube at that end of the apparatus where the said closure member is located.

4. An apparatus for the synthetic production 70 of ammonia in which the member constituting the closure of the outer pressure-supporting tube has an inlet conduit passing therethrough and through which conduit the gases that are to undergo reaction are introduced into the apparatus so as to cool the aforesaid member, and said member also carrying a conduit which constitutes the exit tube for the gases after reaction, said conduit being continued beyond said member so as to project straight-forward into the interior of the pressure-supporting tube and carrying on 75 its extended portion the inner tube containing the catalyzing material, and means whereby the gases that are to undergo reaction are admitted into the space between the outer pressure-supporting tube and the inner tube 80 at that end of the apparatus where the closure member is located.

5. An apparatus for the synthetic production 85 of ammonia in which a member constituting a closure of the outer pressure-supporting tube has an inlet conduit passing therethrough and through which conduit the gases that are to undergo reaction are introduced into the apparatus so as to cool the aforesaid member, and said member also carrying a conduit thermally insulated therethrough which constitutes the exit tube for the gases after reaction, said conduit being continued beyond said member so as to project straight-forward into the interior of the 90 pressure-supporting tube and carrying on its extended portion the inner tube containing the catalyzing material, and means whereby the gases that are to undergo reaction are admitted into the space between the outer pressure-supporting tube and the inner tube 95 at that end of the apparatus where the closure member is located.

6. An apparatus for the synthetic production 100 of ammonia, comprising an outer pressure-supporting tube, an inner tube containing the catalyzing material contained within the said outer tube, a member constituting a closure of the said outer tube, said member and the portion of the outer tube 105 with which it engages being constructed with male and female screw threads of interrupted formation and means being provided for rotating the closure member into and out of engagement, and a conduit which constitutes the exit tube for the gases after reaction carried by the aforesaid member, the said conduit being continued beyond said member so as to project into the interior of the pressure-supporting tube and carrying on its extend- 110

ed portion the aforesaid inner tube containing the catalyzing material.

7. An apparatus for the synthetic production of ammonia, comprising an outer pressure-supporting tube, an inner tube containing the catalyzing material contained within the said outer tube, a member constituting the closure of the said outer tube, said member and the portion of the outer tube with which it engages being constructed with male and female screw threads of interrupted formation, and means being provided for rotating the closure member into and out of engagement, an inlet conduit passing through the said member and through which conduit the gases that are to undergo reaction are introduced into the apparatus so as to cool the aforesaid member, a conduit which constitutes the exit tube for the gases after reaction carried by but thermally insulated from the aforesaid member, the said conduit constituting the exit tube being continued beyond said member so as to project into the interior of the pressure-supporting tube and carrying on its extended portion the aforesaid inner tube containing the catalyzing material.

8. An apparatus for the synthetic production of ammonia, comprising an outer pressure-supporting tube and an inner tube containing the catalyzing material contained within the said outer tube and attached by means such as lag-bolts to a member constituting the closure of the said outer tube, said member carrying a conduit which constitutes the exit tube for the gases after reaction, and said conduit being continued beyond said member so as to project into the interior of the pressure-supporting tube and carrying on its extended portion the aforesaid inner tube containing the catalyzing material.

9. An apparatus for the synthetic production of ammonia, comprising an outer pressure-supporting tube, an inner tube containing the catalyzing material contained within the said outer tube, a member constituting the closure of the said outer tube, said member and the portion of the outer tube with which it engages being constructed with male and female screw threads of interrupted formation, and means being provided for rotating

the closure member into and out of engagement, an inlet conduit passing through the said member and through which conduit the gases that are to undergo reaction are introduced into the apparatus so as to cool the aforesaid member, a conduit which constitutes the exit tube for the gases after reaction carried by but thermally insulated from the aforesaid member, the said conduit constituting the exit tube being continued beyond said member so as to project into the interior of the pressure-supporting tube and carrying on its extended portion the aforesaid inner tube containing the catalyzing material, and additional means such as lag-bolts for attaching the aforesaid inner tube to the closure-forming member.

10. An apparatus for the synthetic production of ammonia, comprising an outer pressure-supporting tube provided with an external heat-insulating covering and an electrical heating circuit within the said covering, said outer tube being constructed and arranged so as to resist the physical and chemical conditions to which it is subjected, an inner tube containing the catalyzing material and constructed with walls having a variable thermal conductivity along the length of said tube, a member constituting the closure of the said outer tube, said member and the portion of the outer tube with which it engages being constructed with male and female screw threads of interrupted formation, and means being provided for rotating the closure member into and out of engagement, an inlet conduit passing through the said member and through which conduit the gases that are to undergo reaction are introduced into the apparatus so as to cool the aforesaid member, and a conduit which constitutes the exit tube for the gases after reaction carried by but thermally insulated from the aforesaid member, the said conduit constituting the exit tube being continued beyond said member so as to project into the interior of the pressure-supporting tube and carrying on its extended portion the aforesaid inner tube containing the catalyzing material.

In testimony whereof I affix my signature.

GEORGES CLAUDE.
